UNITED STATES PATENT OFFICE

JOE CRITES, OF NEW YORK, N. Y., ASSIGNOR TO INTERNATIONAL COMBUSTION ENGINEERING CORPORATION, OF NEW YORK, N. Y., A CORPORATION OF DELAWARE

HIGH-SPEED SCREEN MILL

Application filed June 6, 1929. Serial No. 368,901.

This invention relates to a new and improved high speed screen mill, and particularly to improvements in the mechanism for feeding material into the mill, and for rendering the feeding and grinding elements more accessible for cleaning and repair or replacement purposes.

According to these improvements, the feeding mechanism is arranged at one side of the grinding chamber whereby the material to be ground is fed laterally into the grinding chamber, and the upper portion of the mill housing is in the form of a closure hinged to the main lower housing portion so that the closure or cover may be readily swung back to simultaneously expose both the grinding and feeding mechanisms.

The general object of this invention is to provide a new and improved type of mill, briefly referred to hereinabove, and disclosed more in detail in the specifications which follow.

Another object is to provide an improved removable closure member for the mill.

Another object is to provide an improved form of feeding mechanism for the mill.

Other objects and advantages of this invention will be more apparent from the following detailed description of one approved form of apparatus embodying the principles of the invention.

In the accompanying drawings:

Fig. 1 is a side elevation of the mill, parts being shown in longitudinal vertical section, taken substantially on the line 1—1 of Fig. 2.

Fig. 2 is an end elevation of the mill, parts being shown in section, taken substantially on the line 2—2 of Fig. 1.

Fig. 3 is a horizontal section taken substantially on the line 3—3 of Fig. 2.

Fig. 4 is a perspective view of the rotary feeding element.

Fig. 5 is a vertical section, taken substantially on the line 5—5 of Fig. 1.

Fig. 6 is a vertical section taken substantially on the line 6—6 of Fig. 1.

The mill housing comprises a main lower housing member 1, which encloses the lower half of the grinding chamber 2, and the lower half of the feeding chamber 3, as well as the

lower chamber 4, into which the ground or pulverized material passes. The lower wall of grinding chamber 2 comprises a substantially semi-cylindrical screen 5 supported at its ends and sides by suitable brackets 6 and 7 within the housing 1. The screen 5 will be of appropriate mesh, depending upon the fineness of the material desired, this material passing through the screen into the chamber 4, where it may be collected or from which it may pass downwardly through a chute or passage into some suitable collection receptacle.

The removable closure or cover member 8 of the housing encloses the upper halves of the grinding and feeding chambers 2 and 3, respectively. This cover 8 is provided at one end with brackets 9, by which it is loosely hinged at 10 to brackets 11, secured to the lower housing member 1. The two housing members are normally secured together firmly by a plurality of bolt connections 12 positioned at suitable intervals around the connecting plane between the two members.

The movable grinding element comprises a main supporting shaft 13, to which is secured a spider construction 14, in which are hinged the inner ends of the swing hammers 15, which are thrown outwardly by centrifugal force as the pulverizing member 80 is rotated so as to crush the material contained in chamber 2 by impact and by throwing this material against the top liner or breaker plate 16 secured within the closure member 8, and the screen 5. The end portions of the rotary driven shaft 13 are journaled in roller bearing assemblies 17 and 18 supported in the housing 1. It will be noted that the axis of rotation of shaft 13 lies in the horizontal plane in which the housing members 1 and 8 are joined. One end of shaft 13 is connected by a suitable coupler 19 with the shaft 20 of the driving motor 21, which is mounted on a bracket 22 secured to one side of the lower housing member 1.

Secured to the upper side portion of the main housing 1 opposite the side from which motor 21 is supported, is a hopper housing 23 enclosing a main upper hopper chamber 24, open at its upper end to receive the ma-

terial to be ground or pulverized and communicating at its lower end with the cylindrical chamber 25 which forms an extension of the feeding chamber 3, already referred to. A laterally extending opening or feed passage 26 connects feed chamber 3 with grinding chamber 2. As will be seen from Figs. 1, 3 and 5, this passage is approximately half the height of the feed chamber 3, and of somewhat less length than the width of the assembled rotary grinding element in chamber 2. The rotary feed member 27 is journaled for rotation about a horizontal axis in the communicating feeding chambers 3 and 25, the shaft extension 28 at one end of element 27 being journaled in a bearing 29 formed in one wall of hopper 23, and the shaft extension 30 at the opposite end of element 27 being journaled in bearing 31 formed in the main housing 1. The feeding element 27 is in the form of a section of hollow shafting, on one end portion of which is formed the spiral screw conveyor 32 of a length sufficient to occupy all of the chamber portion 25 and to extend into feeding chamber 3 to a position somewhat beyond the one end of the opening 26, leading to the grinding chamber. On the opposite end portion of element 27 is formed a screw conveyor 33 of opposite pitch to the screw 32 and of a length sufficient to extend from the opposite end of chamber 3 to a position somewhat beyond the adjacent end of opening 26. On that portion of element 27 between the two screw conveyors 32 and 33, is formed a plurality of tangentially projecting paddles or propellers 34 adapted to eject material through opening 26 into the grinding chamber 2. As here shown, these paddles 34 are arranged in pairs extending from diametrically opposite sides of the shaft 27, and the pairs are arranged in staggered relation at 90° with one another, as clearly shown in Figs. 1, 3 and 4.

It will now be apparent that when the feeding element is rotated in the proper direction (clockwise, as seen in Fig. 5), by a mechanism hereinafter described, material fed down by gravity through hopper 24 will be forced into and through the feeding chamber 3, by the screw propeller 32 and then will be ejected by paddle 34 through opening 26 into the grinding chamber 2. Any material that passes beyond the opposite end of opening 26 will be returned into the path of paddle 34 by the screw propeller 33 of opposite pitch.

A rotary agitator 35 of any suitable form is mounted within the hopper chamber 24 and supported on a shaft 36 journaled in the opposite walls of the hopper. A gear 37 keyed on one end of shaft 36 meshes with a gear 38 keyed on shaft 28, whereby the agitator is driven from the feeding element 27 whenever this element is rotated. A remov-

able closure plate 39 closes the chamber 40, formed at one end of the hopper 23 for enclosing the gears 37 and 38. A hand wheel 41 is secured to the projecting end of shaft 28, whereby the rotary feeding element 27 may be rotated by hand when desired.

A small pulley 42 secured to the free end of grinding shaft 13 is connected by belt 43 with the large pulley 44 mounted on one end of counter-shaft 45, journaled in bearings 46 and 47 formed on the upper side of closure member 8. On the opposite end of shaft 45 is keyed a pinion 48 meshing with a large gear 49 mounted on a stub shaft 50 journaled in one side wall of cover member 8 and in the removable gear housing which is secured to the side of the closure 8 and houses the gears 48 and 49. On the outer end of stub shaft 50 is secured a driving crank 51. A link 52 is pivotally connected at its ends with free end portions of crank 51 and a lever 53 fulcrumed at its upper end 54 on the side of housing 8. A slide block 55 is held in adjusted position lengthwise of lever 53 by means of suitable set screws 56. A ratchet wheel 57 is keyed on the outer end of shaft 30, projecting from one end of the rotary feed element 27. A pair of similar pawl carriers 58 and 59 are pivotally mounted on the oppositely extending hub portions of ratchet wheel 57, each pawl carrier comprising an outwardly extending arm and a housing projecting laterally over the periphery of the ratchet wheel, in which are pivoted oppositely projecting pawls 60 and 61 held yieldably in engagement with the ratchet 57 in any suitable manner. Similar links or pitmen 62 and 63 connect the outer portions of the respective pawl carriers 58 and 59 with the slide block 55. It will now be seen that although the grinding shaft 13 is rotating at high speed, the crank 51 will be rotated slowly by means of the reduction gearing comprising belt gearing 42, 43 and 44, and the reducing gears 48 and 49. The slowly rotating crank 51, will, through link 52, oscillate the lever 53 about its fulcrum 54. This lever 53 will in turn oscillate the two pawl carriers 58 and 59 about the axis of ratchet wheel 57, through the connecting links or pitmen 62 and 63 connected with slide block 55. By adjusting the position of slide block 55 toward or away from the fulcrum 54 of lever 53, the stroke of the links 62, 63 and consequently of the pawl carriers 58 and 59 may be varied through certain limits. It will now be apparent that when the two pawl carriers are oscillated in one direction, for example, toward the right in Fig. 2, pawl 60 will engage the teeth of ratchet 57 and impart a certain amount of rotation to this ratchet wheel and the shaft 30. On the return oscillation of the pawl carriers, that is, toward the left in Fig. 2, the other pawl 61 will positively engage the ratchet teeth to impart a further rotation to

the ratchet wheel in the same direction, that is, clockwise, as seen in Fig. 2. In this manner a quite slow and substantially continuous rotation may be imparted to the rotary feeding element 27, and the speed of this movement can be varied within certain limits by adjusting the position of slide block 55 along the oscillating lever 53.

In operation, material fed into the upper open end of hopper 24 will pass downwardly by gravity until it is engaged by the rotating screw propeller 32, the rotary agitator 35 serving to break up this material and prevent clogging of the hopper. The screw propeller 32 will carry this material laterally through the feeding chamber until it is opposite the opening 26, whereupon the paddles 34 will eject the material through opening 26 into the grinding chamber 2. Any material that is not ejected and finds its way to the opposite end of feed chamber 3 will be returned by the screw propeller 33 into the path of paddles 34. It will be seen that the material projected through opening 26 is brought directly into the path of the rotating impact hammers 15, and this material is fed into the grinding chamber gradually and continuously and in constant predetermined amounts, whereby the grinding operation is most efficiently carried out.

When it is necessary or desirable to gain access to the rotary members of the mill, the bolts 12 connecting the cover member 8 with the main housing 1, and bolts 64 connecting cover 8 with the adjacent side housing members are removed, and the belt 43 and the links 62 and 63 are disconnected, whereupon the entire cover member 8 and the parts carried thereby may be swung back about the hinges 10 permitting access simultaneously to the rotary grinding member and to the rotary feed member 27 within feed chamber 3. This permits access to all of the important portions of the apparatus, and if necessary, additional parts can be removed or replaced in an obvious manner. This apparatus is suitable for grinding paint materials, or for a number of similar purposes. It will be noted that mechanism is provided for forcibly feeding the material to be ground into the grinding chamber, continuously and over the full width of the grinding elements, without the use of air or suction, thereby greatly simplifying the mill construction and the necessary auxiliary devices.

I claim:

1. In a pulverizing mill, a mill housing enclosing a pulverizing chamber and a feeding chamber, with a communicating passage therebetween, and movable pulverizing and feeding elements positioned in the respective chambers, the housing comprising a main supporting portion and a removable cover portion, each portion containing substantially half of each chamber whereby both mova-

ble elements will be exposed when the cover is removed.

2. In a pulverizing mill, a mill housing enclosing a pulverizing chamber and a feeding chamber, with a communicating passage therebetween, and movable pulverizing and feeding elements positioned in the respective chambers, the housing comprising a main supporting portion and a removable cover portion, hinged to the main portion, each portion containing substantially half of each chamber whereby both movable elements will be exposed when the cover is swung to open position.

3. In a pulverizing mill, a rotary grinding member, a rotary feed member, the two rotary members being mounted on parallel axes positioned in the same horizontal plane, means for driving the rotary members, and a mill housing enclosing a pulverizing chamber and a feed chamber adapted to house the grinding and feed members respectively, there being a communicating feed opening between the chambers, the housing comprising a fixed main housing member and a removable closure member, the two members being joined in the horizontal plane of the axes of the rotary members.

4. In a screen mill, a rotary grinding member, a rotary feed member, the two rotary members being mounted on parallel axes positioned in the same plane, means for driving the rotary members, and a mill housing enclosing a pulverizing chamber and a feed chamber adapted to house the grinding and feed members respectively, there being a communicating feed opening between the chambers, the housing comprising a fixed main housing and a removable closure member, the two members being joined substantially in the plane of the axes of the rotary members.

5. In a screen mill, a rotary grinding member, a rotary feed member, the two rotary members being mounted on parallel axes positioned in the same horizontal plane, means for driving the rotary members, and a mill housing enclosing a pulverizing chamber and a feed chamber adapted to house the grinding and feed members respectively, there being a communicating feed opening between the chambers, the housing comprising a fixed main housing member and a removable closure member hinged to the main member so that it may be swung back to simultaneously expose both of the rotary members, the two housing members being joined in the horizontal plane of the axes of the rotary members.

6. In a screen mill, a rotary grinding member, a rotary feed member, the two rotary members being mounted on parallel axes positioned in the same plane, means for driving the rotary members, and a mill housing enclosing a pulverizing chamber and a feed chamber adapted to house the grinding and

feed members respectively, there being a communicating feed opening between the chambers, the housing comprising a fixed main housing and a removable closure member hinged to the main member so that it may be swung back to simultaneously expose both of the rotary members, the two housing members being joined substantially in the plane of the axes of the rotary members.

10. 7. In a screen mill, a rotary grinding member, a rotary feed member, the two rotary members being mounted on parallel axes positioned in the same horizontal plane, a mill housing enclosing a pulverizing chamber and a feed chamber adapted to house the grinding member and the feed member respectively, there being a communicating feed opening between the chambers, the housing comprising a main housing member and a removable closure member joined to the main member in the horizontal plane of the axes of the rotary members, a motor mounted on the main housing member for driving the grinding member, and reduction gearing connecting the grinding member with the feed member.

8. In a screen mill, a rotary grinding member, a rotary feed member, the two rotary members being mounted on parallel axes positioned in the same horizontal plane, a mill housing enclosing a pulverizing chamber and a feed chamber adapted to house the grinding member and the feed member respectively, there being a communicating feed opening between the chambers, the housing comprising a main housing member and a removable closure member hinged to the main member in the horizontal plane of the axes of the rotary members, a motor mounted on the main housing member for driving the grinding member, and reduction gearing connecting the grinding member with the feed member.

15. 9. In a screen mill, a rotary grinding member, a rotary feed member, the two rotary members being mounted on parallel axes positioned in the same horizontal plane, a mill housing enclosing a pulverizing chamber and a feed chamber adapted to house the grinding member and the feed member respectively, the housing comprising a main housing member and a removable closure member joined to the main member in the horizontal plane of the axes of the rotary members, a motor mounted on the main housing member for driving the grinding member, and reduction gearing connecting the grinding member with the feed member, a portion of this reduction gearing being carried by the removable closure member.

20. 10. In a screen mill, a rotary grinding member, a rotary feed member, the two rotary members being mounted on parallel axes positioned in the same horizontal plane, a mill housing enclosing a pulverizing chamber and a feed chamber adapted to house the

grinding member and the feed member respectively, the housing comprising a main housing member and a removable closure member joined to the main member in the horizontal plane of the axes of the rotary members, a motor mounted on the main housing member for driving the grinding member, and reduction gearing connecting the grinding member with the feed member, a hopper mounted on the main housing member and communicating with the feed chamber, an agitator in the hopper and means for driving the agitator from the rotary feed member.

11. In a screen mill, a housing enclosing a grinding chamber and a feed chamber positioned at one side thereof, there being a communicating feed passage connecting the chambers, a pulverizing element movable in the grinding chamber, and mechanical means positioned in the feed chamber for positively conveying material thereinto and ejecting same through the feed passage into the path of the pulverizing element in the grinding chamber.

12. In a screen mill, a housing enclosing a grinding chamber and a feed chamber positioned at one side thereof, there being a communicating feed passage connecting the chambers, a pulverizing element movable in the grinding chamber, a hopper communicating with the feed chamber at a point removed from the feed passage, and mechanical means positioned in the feed chamber for positively conveying material from the hopper and ejecting same through the feed passage into the path of the pulverizing element in the grinding chamber.

13. In a screen mill, a housing enclosing a grinding chamber and a substantially cylindrical feed chamber positioned at one side of the grinding chamber, there being a communicating opening between the adjacent sides of the chambers, a rotary grinding element in the grinding chamber, a rotary feeding element in the feed chamber, means for rotating the two elements, and a hopper communicating with a portion of the feed chamber laterally removed from the opening between the two chambers, the feeding element being journaled for rotation on the axis of the cylindrical feed chamber and comprising a screw propeller for conveying material to the opening, and paddles for propelling material through the opening into the grinding chamber.

14. In a screen mill, a housing enclosing a grinding chamber and a substantially cylindrical feed chamber positioned at one side of the grinding chamber, there being a communicating opening between the adjacent sides of the chambers, a rotary grinding element in the grinding chamber, a rotary feeding element in the feed chamber, means for rotating the two elements, and a hopper com-

5 municating with a portion of the feed chamber laterally removed from the opening between the two chambers, the feeding element being journaled for rotation on the axis of the cylindrical feed chamber and comprising a screw propeller positioned beneath the hopper and leading up to the opening to the grinding chamber, and paddles opposite this opening for propelling material through the 10 opening into the grinding chamber.

15. In a screw mill, a housing enclosing a grinding chamber and a substantially cylindrical feed chamber positioned at one side of the grinding chamber, there being a communicating opening between the adjacent sides of the chambers, a rotary grinding element in the grinding chamber, a rotary feeding element in the feed chamber, means for rotating the two elements, and a hopper communicating with a portion of the feed chamber laterally removed from the opening between the two chambers, the feeding element being journaled for rotation on the axis of the cylindrical feed chamber and comprising a screw propeller positioned beneath the hopper and leading up to the opening to the grinding chamber, a screw propeller of opposite pitch positioned beyond the opening, and paddles opposite the opening for forcing 30 material through the opening into the grinding chamber.

16. In a screen mill, a housing enclosing a grinding chamber and a substantially cylindrical feed chamber positioned at one side of the grinding chamber, there being a communicating opening between the adjacent sides of the chambers, a rotary grinding element in the grinding chamber, a rotary feed element in the feed chamber, means for rotating the two elements, and a hopper communicating with a portion of the feed chamber laterally removed from the opening between the two chambers, the feeding element being journaled for rotation on the axis of the cylindrical feed chamber and comprising a screw propeller positioned beneath the hopper and leading up to the opening to the grinding chamber, a screw propeller of opposite pitch positioned beyond the opening, and paddles opposite the opening for forcing material through the opening into the grinding chamber, and an agitator in the hopper driven from the rotary feeding element.

17. In a screen mill, a housing enclosing a grinding chamber and a substantially cylindrical feed chamber positioned at one side of the grinding chamber, there being a communicating opening between the adjacent sides of the chambers, the housing comprising a main lower portion and a removable cover portion, each portion containing substantially half of each chamber, a rotary grinding element in the grinding chamber, a 60 motor for driving the grinding element, a

bracket on the main housing member for supporting the motor, a rotary feeding element in the feed chamber, adjustable reduction gearing for driving the feed element from the grinding element, a hopper communicating with the feed chamber, an agitator in the hopper, and means for driving the agitator from the feed element. 70

18. In a screen mill, a housing enclosing a grinding chamber and a substantially cylindrical feed chamber positioned at one side of the grinding chamber, there being a communicating opening between the adjacent sides of the chambers, the housing comprising a main lower portion and a removable cover portion, each portion containing substantially half of each chamber, a rotary grinding element in the grinding chamber, a motor for driving the grinding element, a bracket on the main housing member for supporting the motor, a rotary feed element in the feed chamber, adjustable reduction gearing for driving the feed element from the grinding element, a hopper communicating with the feed chamber, an agitator in the hopper, means for driving the agitator from the feed element, the feed element being journaled for rotation on the axis of the cylindrical chamber and comprising a screw propeller for conveying material from the hopper to the opening leading to the grinding chamber, a screw propeller at the opposite side of this opening for returning material thereto, and paddles opposite the opening for propelling the material through the opening into the grinding chamber. 80

19. In a pulverizing mill, a housing enclosing a grinding chamber and a substantially cylindrical feed chamber at one side of the grinding chamber, there being a communicating opening between the adjacent sides of the chambers, and a rotary feeding element in the feed chamber comprising a screw propeller for conveying material to the opening, and paddles for propelling the material through the opening into the grinding chamber. 100

20. In a pulverizing mill, a housing enclosing a grinding chamber and a substantially cylindrical feed chamber at one side of the grinding chamber, there being a communicating opening between the adjacent sides of the chambers, and a rotary feeding element in the feed chamber comprising a screw propeller for conveying the material to the opening, a screw propeller of opposite pitch positioned beyond the opening, and paddles opposite the opening for forcing the material through the opening into the grinding chamber. 110

21. In a pulverizing mill, a mill housing enclosing a pulverizing chamber and a feeding chamber, and movable pulverizing and feeding elements positioned in the respec- 125

tive chambers, the housing comprising a main supporting portion in which the movable elements are mounted and a removable cover portion which contains a substantial part of each chamber whereby both movable elements will be exposed when the cover is removed.

JOE CRITES.
